United States Patent Office

Des. 194,435
Patented Jan. 22, 1963

194,435

GAUGE

Ralph G. Sanders, Lake Villa, Ill., assignor to Ammco
Tools, Inc., Chicago, Ill., a corporation of Illinois

Filed Jan. 2, 1962, Ser. No. 68,142

Term of patent 14 years

(Cl. D52—6)

Fig. 5.

FIGURE 1 is a front view of the gauge showing my new design;

FIG. 2 is a top view;

FIG. 3 is a view looking toward the left-hand end, as viewed in FIGURE 1;

FIG. 4 is a rear elevational view thereof in an extended position;

FIG. 5 is a bottom view of the gauge in an extended position; and

FIG. 6 is a view looking toward the right-hand end of FIGURE 1.

I claim:
The ornamental design for a gauge, substantially as shown.
